Smart headband scarf (on-line), posted Jun. 11, 2014 on Valentine Maid and company Facebook page. Retrieved from Internet Oct. 14, 2015, URL: <https://www.facebook.com/520597031355634/photos/a.640787512669918.1073741825.520597031355634/640787536003249/?type=3&theater> (1 page).*

Primary Examiner — Karen E. Eldridge Powers*Assistant Examiner* — Kimberly Barnes(74) *Attorney, Agent, or Firm* — Suiter Swantz pc llo**CLAIM**

The ornamental design for a headband scarf, as shown and described.

DESCRIPTION

FIG. 1 is a perspective view of the headband scarf showing my new design;

FIG. 2 is a top plan view thereof;

FIG. 3 is a front elevation view thereof;

FIG. 4 is a first side elevation view thereof;

FIG. 5 is a rear elevation view thereof;

FIG. 6 is a second side elevation view thereof; and,

FIG. 7 is a bottom plan view thereof.

The broken lines shown in the drawings are stitching, and form part of the claimed design.
